UNITED STATES PATENT OFFICE.

JOHN J. LAWLER, OF PLAINFIELD, NEW JERSEY, ASSIGNOR TO NEW PROCESS MULTI-CASTINGS COMPANY, A CORPORATION OF NEW JERSEY.

MOLDING MACHINE.

Application filed October 20, 1926. Serial No. 142,907.

The present invention relates to mold making machines and particularly to that class of machines where one or more of the flask parts are attached to the machine, although the invention in some of its aspects is adapted for embodiment in machines using a separate flask for each mold.

The primary object of the present invention is to provide mechanism which eliminates the hand ramming found to be necessary as a finishing operation for packing molding sand in a flask; particularly around the edges thereof, even where the machine includes a jarring table or a squeeze head or plate or both.

Another object of the invention is to provide mechanism for this purpose which is adapted at times to overlie the flask, and at times to be moved clear thereof in order that the flask may be readily filled with sand.

A further object is to provide such mechanism which can be readily raised and lowered with respect to the flask.

A still further object is to provide such a device which is so mounted as to have free vertical reciprocating movement with respect to the flask filled with sand and which, when used in combination with a jarring table, descends upon the sand, packing it in the flask at the end of each jarring stroke, being lifted on the sand on the upward stroke and following down on the sand by gravity and packing the sand in the flask upon each downward stroke thereof during jarring.

Other and further objects of the invention will appear from the following description taken in connection with the accompanying drawings, which illustrate, by way of example, a preferred embodiment of the invention, but which are not to be taken as a definition of the limits thereof, reference being had to the appended claims for that purpose.

In the drawings:

Fig. 1 is a side elevation of one form of molding machine embodying the present invention and showing, somewhat diagrammatically, the control valves and necessary pipe lines for operating the machine by compressed air or other fluid;

Fig. 2 is a side elevation, partly in section, on an enlarged scale, illustrating a part of the machine shown at the left of Fig. 1 and

showing the sand packing follower plate in lowered position;

Fig. 3 is a side elevation, partly in section, on a somewhat smaller scale, and showing the flask in raised position with respect to the jarring table and showing the sand packing follower member also in raised position;

Fig. 4 is an end view of the machine of Fig. 3, but showing the flask lowered upon the jarring table and the sand packing follower member in raised position;

Fig. 5 is a sectional detail view taken on the line 5—5 of Fig. 2;

Fig. 6 is a fragmentary detail view showing a tucking flange on the sand packing follower member;

Fig. 7 is a sectional detail view through the sand packing follower member shaft bearing.

Referring in detail to the drawings and particularly to Fig. 1, the invention is shown as being embodied in and forming a part of a so-called double machine, in which the flask parts are attached to the machine and are adapted to produce successively as many molds as may be required, one portion of the machine, as herein shown that portion on the left side of Fig. 1, being adapted to make successively a plurality of drag molds, and the other portion of the machine, as herein illustrated that portion of the machine on the right side of Fig. 1, being adapted to make successively a plurality of cope molds and deposit them upon the drag molds. In this form of machine, owing to the rapidity with which the completed molds stripped of their flasks are produced, it is desirable that some form of assembly and transfer table be provided not only for the purpose of permitting the molds to be closed thereon, but also to remove the continuously produced molds from the machine for pouring.

Accordingly, in Fig. 1 there is shown a drag mold jarring table 11, on which rests the drag pattern 12, upon which rests the drag 13 and bottom board 14. The drag and drag pattern are carried by a pair of horizontal arms 19 for free vertical reciprocating movement with respect to said arms. The arms 19 are formed on or carried by a sleeve member 20 fixed to the vertical cylinder 21, which is movable upwardly and downwardly with respect to a stationary piston 22 fixed

in the boss 23 on the base 24 of the machine. A control valve 25 is shown as being provided with suitable pipe lines leading to the jarring table and to the flask raising and lowering cylinder 21.

The cope mold jarring table 30 is provided with a cope pattern, upon which is adapted to rest during jarring the cope 31 carried for free vertical reciprocating movement in the outer ends of the cope arms 32 carried by the vertically movable cylinder 33, which is raised and lowered by compressed air delivered to it through suitable pipe lines and controlled by the valve 34, which, in the present embodiment of the invention, also controls the cope jarring table 30. A mold assembly and transfer table, indicated generally at 35, is placed between the cope mold forming part of the machine and the drag mold forming part of the machine. As shown in Fig. 1, the mold assembly and transfer table may comprise vertical side standards 37 carrying at their upper ends a pair of longitudinally extending parallel stationary rails 38, to which are secured the downwardly and inwardly extending brackets 39 carrying the grooved rollers 40, upon which a lower pair of connected parallel guide rails 42 are adapted to travel back and forth. Secured by links 43 to the rails 42 are an upper pair of connected parallel mold lifting and transfer rails 46 adapted at times to descend and rest upon the lower guide rails 42, lowering a mold upon the stationary rails 38, and at times to lift the mold from said stationary rails and carry it away from the machine. This or similar mechanism is found to be highly desirable with such a machine as that herein described in order to provide mechanical means for carrying off the molds which are produced very rapidly by the machine.

Referring now more particularly to Fig. 2, which shows in sectional elevation the interior of the drag mold carrying cylinder at the left-hand side of Fig. 1, upon a suitable foundation is mounted the base 24, which supports the jarring table casing 51, within which is located the jarring cylinder and piston for jarring the drag table 11. The stationary piston 22 is fixedly mounted to the base of the machine within a deep annular flange 57, in which the piston is keyed, as at 58, to prevent relative movement of the piston with respect to the base of the machine. The upper end of the piston is provided with a central opening, within which is secured a threaded abutment plug 59, the upper surface of which is provided with a plurality of radial channels and air inlet ports 61. A packing plate 62 is provided on the top surface of the upper end of the piston 22 secured thereto by bolts or other means, and the under side of the head 42 is recessed to provide clearance for such bolts and to per-

mit the cylinder head 63, in lowered position, to abut against the upper face of the plug 59, upon which the weight of the cylinder 21 is carried in its lowered position, the radial channels in the face of the plug 59 communicating with the air inlet ports 61, permitting air to travel from the interior of the piston to the expanding chamber between the piston and cylinder head.

A guiding lug 66 secured to the cylinder 21 and projecting inwardly thereof is adapted to travel vertically in either of two longitudinally extending grooves 67 and 68 provided in the present instance 180° apart in the outer circumferential surface of the piston 56. At the upper end of the piston 22 a circumferential groove 69 is provided, connecting the two longitudinal grooves 67 and 68. It will thus be seen that the lug 66, traveling vertically in groove 67, guides the cylinder as the flask is raised and lowered over the operating table 11 and that when the cylinder 21 is in its upper position with respect to the piston, the lug 66, entering the semicircular groove 69, may travel circumferentially therearound as the cylinder 21 rotates in a semicircle with respects to the piston until the lugs 66 arrives above the vertical groove 68, at which time the cylinder 21, having moved through 180° in the present embodiment of the invention and carrying the drag flask with it, may be lowered to deposit the drag section of the mold on the assembly and transfer table 35, being guided vertically in its downward movement by the guide lug 66 traveling in longitudinal groove 68 of the piston. The head 63 of the cylinder 21 is provided with the vertically extending cylindrical projection 75, which revolvably carries the sleeve portion 76 of an arm 77, which carries the sand packing follower device of the present invention, as will be described more particularly hereinafter. The drag pattern 12 is provided with the bottom board clamping hooks 80 and the drag positioning pins 81, which accurately locate the drag 13 upon the drag pattern. A sand frame 85, open at its top and bottom, is adapted to fit around the upper edge of the drag 13 and is positionable thereon by guide pins received within openings in the upper edge of the drag 13. Fig. 2 shows the sand frame filled with sand and the sand packing follower device lowered upon and resting on the sand within the sand frame 85.

Air is admitted to the cylinder 21 for the purpose of raising the flask with respect to the table 11, through pipe 92 threaded into the lower head 93 of a cylindrical casing 94 secured at its upper end to the threaded abutment plug 59 and in communication with the openings 61 of said plug to admit air or other fluid under pressure into the expandable chamber between the cylinder head 63 and piston 56. Suitable shock absorbing means

is provided by the invention for preventing the cylinder from stopping suddenly at the limit of its upward movement, and, as herein shown, a depending rod 96, threaded at its upper end into the cylindrical projection 75 of the cylinder head, is provided at its lower end with an enlargement or head 98, upon which rests the coil spring 99 surrounding the rod 96 and adapted, near the end of the upward stroke of the cylinder, to strike against the under side of the abutment plug 59 to absorb shock in the stopping of the cylinder 20. During upward movement of the cylinder, the rod 96 moves upwardly through the central portion of the abutment plug 59.

The vertically extending cylindrical projection 75 revolvably carries the sand packing follower plate supporting arm 77, which, as shown in the present embodiment of the invention, is integral with or secured to the sleeve member 76 rotatably mounted on the projection 75. A positioning detent 100 is provided in the sleeve and is adapted to enter a depression in the projection 75 for the purpose of accurately positioning the arm 77 and the sand packing follower member over the flask.

The invention provides means for lifting and maintaining in lifted position the sand packing follower member with respect to the flask, and also provides means for lowering said member and releasing it to permit free vertical reciprocating movement thereof during jarring of the flask.

For this purpose, in the embodiment of the invention herein illustrated, the arm 77 has secured to or formed on its outer end a bearing member 103 having a central vertical aperture extending therethrough, in which is located the shaft 105 which is keyed to reciprocate rectilinearly in said bearing and which carries at its lower end the sand packing follower member 106. The shaft 105 is freely movable up and down in the bearing 103, and is provided at its upper end with cam rollers 108 and 109 revolvably mounted on a cam roller shaft 110 passing horizontally through the vertical shaft 105. The cam rollers 108 and 109 are adapted, respectively, to ride upon the cams 112 and 113 provided on the actuating lever 115, which is pivotally mounted with respect to the bearing 103 as shown at 116. A detent 118 is provided in the actuating lever 115 for the purpose of maintaining said lever in raised or lowered position. When the lever 115 is lowered, the cam rollers 108 and 109, as shown in Fig. 3, are cammed upwardly by the cams 112 and 113, the detent 118 locking the parts in this position and the cam rollers resting in small depressions 121 formed at the ends of the cams 112 and 113. To bring the sand packing follower member to operative position, the lever 115 is raised to the position of Fig. 2, causing the cam rollers to ride downwardly on the cams

and thus lowering the shaft 105, and permitting the sand packing follower member 106 to rest upon the sand contained in the frame 85, the flask 13 and the pattern 12. The lever 115 is maintained in raised position by the detent 118, thus leaving the shaft 105 clear for free vertical reciprocating movement. When the flask is to be filled, the sand packing follower member is raised by the actuating lever 115 and the arm 77 is swung horizontally about the projection 75 to leave free and unobstructed space above the flask while it is being filled with sand.

Referring to Fig. 1, it will be obvious that the cope mold making section of the machine is preferably provided with the identical sand packing follower member and associated mechanism already described.

The operation is as follows: Referring particularly to Fig. 2, assuming it is desired to make a drag mold, the drag 13 is placed on the drag pattern 12 carried by arms 19, and the frame 85 is placed on the drag 13. Molding sand is now introduced into the drag and pattern sufficient to extend above the top of the frame 85. The arm 77 is now swung into position over the flask and the lever 115 is raised to the position of Fig. 2, permitting the cam rollers to ride down on the cams, and thus lowering the shaft 105 and the sand packing follower member 106 down to rest upon the sand, as shown in Fig. 2. The control valve 25 is now moved to jarring position, and during jarring of the table 11 the frame, flask and pattern move up and down in the guide bearings of the arms 19. On the upstroke the sand packing follower member 106 is lifted with the sand, and on the downstroke the sand packing follower member comes down by gravity with the sand and packs it into the frame and flask at the end of the downward jarring stroke during each jar. The sand packing follower member 106 is adapted to descend into the frame 85 during this operation and, if desired, it may be provided with tucking flanges at its ends for the purpose of packing the sand more efficiently about the edges of the flask 113. When sufficient jarring and packing has occurred, the lever 115 is lowered, causing the cam rollers 108 and 109 to ride upwardly on the cams 112 and 113, thereby raising the shaft 105 and sand packing follower member 106 up off the sand, the detent 118 holding the parts in this position. The arm 77 is now swung in a horizontal plane to remove the sand packing follower mechanism from its position over the flask. The frame 85 is now removed and the surplus sand struck off above the upper edges of the drag 13. Any suitable form of bottom board is now placed upon the filled and packed drag and secured in position by retaining hooks 80 in the usual manner. The valve 25 is now operated to raise the cylinder 21, and hence

the filled drag and pattern, above the table 11, into a position where the drag may be rolled over on its trunnions 132 rotatably mounted in the guide blocks 134 vertically movable in the outer ends of the arms 19. When the drag assembly has been rolled over, the cylinder 21 is rotated about the piston 56 until the rolled over drag is brought above the assembling and transfer table 35, whereupon the valve 25 is operated to lower the cylinder 70 on the piston 56 until the bottom board rests upon the table. The hooks 80 are now released and the cylinder 70 is raised vertically by operating valve 25 to draw the pattern 12. The arm 70 is again brought to its former position, shown in Fig. 2.

Meanwhile, by similar steps, a cope mold has been made in the cope 31, which, without being rolled over, is lowered upon the drag mold resting on the table 35 to close the mold, the cope pattern being drawn as the cope is lifted off the cope pattern which is secured to the cope operating table 30. When the cope mold has been lowered on the drag mold, the cope cylinder is raised to strip the mold and return to its former position. The drag 13 is now lifted off the assembled mold and returned to its position on the drag pattern 12, and the process is repeated. The table 35 not only serves as an assembling table, but also as a transfer table to remove the molds as soon as they are closed.

It will thus be seen that the present invention provides mechanism particularly adapted to a jarring machine and which packs the sand down into the flask from above at each stroke of the jarring operation. This mechanism eliminates the customary and usual hand work to pack the sand in the flask, particularly around the flask edges. It is to be observed that the sand packing follower member is freely vertically movable during operation and may be lifted up off the sand and held in raised position and may also be swung in a horizontal plane out of the way for filling the flask.

What is claimed is:

1. In a molding machine, a jarring table for jarring a flask containing molding sand, relatively movable piston and cylinder members, a flask carried by one of said members and movable vertically with respect thereto, and a sand packing follower member carried by one of said members and freely vertically movable with respect thereto, for packing sand in said flask during jarring thereof.

2. In a molding machine, a jarring table for jarring a flask containing molding sand, a stationary piston, a cylinder member vertically movable thereon, a flask carried by

said cylinder over said jarring table, an arm carried by said cylinder over said flask, a shaft mounted in said arm for vertical reciprocating movement therein, a sand packing follower member fixed to said shaft and adapted to pack sand in said flask during jarring, means for raising said shaft and holding it in raised position, means for releasing said shaft to permit free vertical reciprocating movement of said shaft and of said sand packing follower member on the sand in said flask during jarring.

3. In a molding machine, a jarring table for jarring a flask containing molding sand, a stationary piston, a cylinder member vertically movable thereon, a flask carried by said cylinder over said jarring table, an arm carried by and rotatable on said cylinder over said flask, a shaft mounted in said arm for vertical reciprocating movement therein, a sand packing follower member fixed to said shaft and adapted to pack sand in said flask during jarring, means for raising said shaft and holding it in raised position, means for releasing said shaft to permit free vertical reciprocating movement of said shaft and of said sand packing follower member on the sand in said flask during jarring.

4. In a molding machine, a jarring table for jarring a flask containing molding sand, sand packing follower means mounted for free vertical movement above said table for packing sand in said flask during jarring thereof, means for guiding said sand packing follower means vertically for free reciprocating movement in a straight line during jarring, said sand packing follower means being pivotally mounted to swing in a horizontal plane into position over said jarring table or away from such position, and cam means for raising said sand packing follower means to inoperative position.

5. In a molding machine, a jarring table for jarring a flask containing molding sand, sand packing follower means mounted for free vertical movement above said table for packing sand in said flask during jarring thereof, means for guiding said sand packing follower means vertically for free reciprocating movement in a straight line during jarring, said sand packing follower means being pivotally mounted to swing in a horizontal plane into position over said jarring table or away from such position, and lever-operated cam means for raising or lowering said sand packing follower means in a straight vertical line.

In testimony whereof I affix my signature.

JOHN J. LAWLOR.
